UNITED STATES PATENT OFFICE.

JOHN H. LUDWIG, OF NEW YORK, N. Y.

PIANOFORTE.

SPECIFICATION forming part of Letters Patent No. 608,693, dated August 9, 1898.

Application filed August 28, 1897. Serial No. 649,813. (No model.)

To all whom it may concern:

Be it known that I, JOHN H. LUDWIG, a citizen of the United States, and a resident of the city of New York, in the county of New York and State of New York, have invented certain new and useful Improvements in Pianofortes, of which the following is a specification.

This invention relates to improvements in pianofortes, and especially to the scale-bridge 10 bar of the same.

The object of my invention is to provide a new and improved adjustable scale-bridge bar which extends across the strings on the sides at which the hammers are located, and 15 which bridge-bar is adjustable as to its bearing upon the strings, thus permitting of adjusting or regulating the pressure of the bridge-bar on the strings and thereby the pressure of the strings on the wooden bridge 20 on the sounding-board, and thereby permitting of restoring to the sounding-board its full vibratory power at all times and rendering the tone fuller, sounder, less metallic, and of 25 more beauty than has been possible in the pianos as constructed heretofore.

In the accompanying drawing, forming a part of this specification, a vertical transverse sectional view through part of the sounding-board and metal frame and through 30 the scale-bridge bar is shown, parts of the latter being in perspective view.

The pianoforte has the conventional metal frame A, which, however, is provided at the top with the shoulder B, which rests and 35 bears against the wooden wrest-plank C of the wooden frame, and above said shoulder the metal frame A has an upward extension D in a plane in front of that of the plate proper, said extension resting on the wooden 40 plank or bar C, as shown, and to which it is fastened by screws. (Not shown.)

Heretofore that part of the metal frame A resting against the wooden plank or bar C was in the same plane as the rest of the frame 45 A, whereas in my construction it is in a plane in advance of the frame proper, for a purpose that will be set forth hereinafter.

The tuning-pins E are driven through suitable holes in the frame extension D into the 50 plank or bar C, as shown.

The strings F are secured at one end to metal pegs or pins G on the frame A in the

usual manner, and their other ends are secured to the tuning-pins E, and the strings rest on and bear against the wooden bridge 55 H, secured on the sounding-board J, as in the pianos as constructed heretofore.

The scale-bridge bar K, made of metal, papier-mâché, or any other suitable hard substance, extends across the strings F on the 60 outer sides—that is, on the sides on which the hammers L strike—and is preferably provided along the lower edge with a lip M, which comes in contact with the strings, and at its upper edge and inner side it rests on a series 65 of pins or analogous supports N, secured to and projecting upward from the plate A.

Screws O or analogous devices are used to hold the scale-bridge bar K in place and to press its lip M against the strings F. The 70 screws are screwed into the plate A, or, if desired, they may be screwed into a wooden block interposed and secured between the frame A and the sounding-board.

By means of the screws O or analogous adjusting devices the lip M of the bridge-bar K is tilted toward and pressed against the strings F, which at the point of contact with said lip are pressed toward the frame A and sounding-board J, and for this reason the tuning-pins E must project a greater distance from 75 the plane of the frame A, so as to permit of an inward inclination from the pin to the lip M, as shown at F'. In order to take up the strain of these extended pins E, the extension 80 85 D has been located in a plane in advance of that of the frame A proper.

The hammers L strike the strings F at points of desired striking distances varying with the length of the string from the lip M, 90 and the strain produced by the impact is in the same direction as that produced by the lip M. The scale-bridge can be made of a single continuous piece, but is preferably made in sections, conforming in size to the 95 distance between the braces on the frame A. It is evident that with this construction the greater part of the force of the concussion by the blow of the hammer is transmitted to wooden bridge H, and by the latter to the 100 sounding-board J, whereas in the pianos heretofore which have a rigid scale-bridge over which the strings pass a great part of the force of concussion by the hammer-blow is taken up

by the rigid bridge and hence is lost. On account of the absence of this rigid bridge in my construction the tone is much improved in power and expansion for the reason that 5 the full benefit of the hammer-blow is transmitted to the sounding-board.

The sounding-board is rendered much more sensitive, and thus instantly responsive.

As the piano becomes older and the sounding-board relaxes from the strain of the strings 10 pressing on the sounding-board bridge and sounding-board, the necessary strain or pressure of the strings being removed thereby can be readily increased or restored and adjusted 15 by screwing the bridge-bar K down more firmly toward the strings and the original relationship and the full original vibratory power of the sounding-board restored in a most simple and effective manner. The strain 20 on the strings is also reduced by my improved bridge-bar, as there is only one point of friction on the strings between the wooden bridge and the tuning-pins, and thus tuning is greatly facilitated.

25 Having thus described my invention, what I claim as new, and desire to secure by Letters Patent, is—

1. In a pianoforte, the combination with the metal frame and sounding-board and the

usual wooden bridge on the sounding-board, 30 of pins and tuning-pins, of strings secured to the said pins and resting on the bridge only and on no other support between their attachments to the pins, and an adjustable scale-bridge bar resting on the strings between the tuning-pins and the wooden bridge, and means for adjusting the pressure of said bridge-bar on the strings, substantially as herein shown and described. 35

2. In a pianoforte, the combination with a 40 wrest-plank, of a metal frame having a shoulder and an extension beyond said shoulder, the shoulder resting against one edge of the plank and the extension on the adjacent face of the plank, tuning-pins passed through said 45 extension into the plank, strings attached to said tuning-pins, and an adjustable bridge-bar extending across and resting on said strings, substantially as herein shown and described. 50

In testimony that I claim the foregoing as my invention I have signed my name, in presence of two witnesses, this 20th day of August, 1897.

JOHN H. LUDWIG.
